UNITED STATES PATENT OFFICE

FREDERICK H. VAN LOOZEN, OF LOS ANGELES, CALIFORNIA

MULTICOLOR-PRINTING PRESS

Application filed April 9, 1928. Serial No. 268,744.

This invention relates to printing presses and more especially to presses having rotary impression cylinders or platens and a rotary type or form cylinder.

5 The general object of the invention is to accomplish multicolor printing on a sheet of any suitable material which is in continuous action and is repeatedly subjected to impressions on forms carried by a single support 10 and while the sheet is under control of a single impression device which is common to all of the forms. In other words an object is to provide a press having a single unit carrying a multiplicity of forms and a single 15 impression unit which is operative to simultaneously press a respective group of sheets to respective forms, and to provide for the automatic advance of each sheet from the first color form to the final color form during a continuous operation of the press.

A further object is to provide a press having a gang of sheet gages and a row of respective printing forms and means to progressively switch the printed sheets from the 25 printing means back to coordinate gages for advance step by step to successive forms.

An additional object is to provide a press operative to run through, simultaneously, a number of different jobs all unicolor, or each 30 of a different color, or to run different jobs at one time some being multicolor work.

A desideratum is to provide a multicolor inking means operative to ink the forms and including rollers having sections to keep the 35 different colors in their respective zones without intermixing.

Another object is to provide a "fool-proof" sheet gripping means wherein grippers are automatically brought to their proper position when the press starts.

Another purpose of the invention is to provide a form cylinder and means for bodily shifting the cylinder from and to operative position for "throw-off" action without 45 stopping the press motion.

There are other objects, advantages and features of construction, combination and arrangement, and details of means as will be made manifest in the ensuing specification of the herewith illustrative embodiment;

it being understood that modifications, variations and adaptations may be resorted to within the spirit, scope and principle of the invention as it is more directly claimed hereinafter.

Figure 12 is a sectional elevation of the retractor.

80

Figure 13 is a broken away plan of the roller system for automatically registering a sheet in the registering gage stations.

Figure 14 is an end view of the roller system; its frame being in section.

Figure 15 is an elevation of a side shift gage.

85

In its illustrated embodiment the press includes a form cylinder 2 to which may be secured a longitudinal row of curved type forms or plates F; the cylinder having on one end a gear 3 and is fixed on a cross, main cam shaft 4 which times most of the operative mechanism of the press in the ratio of one action to two rotations of the impression cylinder 5.

90

The cylinder 5 is fixed on its shaft 6 and has an end gear 7 meshing with its two-to-one gear 3. This gear 3 is driven by a pinion 8 which is fixed on a drive shaft 9 carrying a fly-wheel 10. The cylinders 2 and 5 have mutual rim tracks 11 and 12 at their ends.

100

A feature of this invention is the means for effecting a quick "throw-off" of the printing action and for this purpose the main shaft 4 is journaled in bearing blocks 13 which are vertically slidable in guideways in the press frame 15. The blocks 13 are mounted on cam hubs 16, of levers 17, which have low spots 16^a. Manual throw-off levers 18 are connected to the cam levers 17 and when it is desired to prevent impressions, without stopping the press, the levers 18 (operative from either side of the press) are pulled up and the cams 16 are turned to drop the cylinder 2 enough to prevent printing impressions. A reverse action of the levers 18 restores printing relation.

The impression cylinder, which will be hereinafter called the platen is provided with the usual tympan and has a longitudinal rock-shaft 20 on which is fixed a gang of gripping claws 21 to pinch a sheet of stock, in a previously registered position, to the platen surface so as to be carried around with it and get an impression from the form 25 (or forms) F.

One purpose of this invention is to provide a "fool-proof" tripping means whereby the gripper will be automatically thrown to gripping position in the event that they 30 should be accidentally left in open position. In other words an object is to eliminate possibility of destruction, or injury of the parts in any position thereof.

Therefore a gripper tripping means is 35 provided which includes a double acting throw-over lever 22 fixed on the rock-shaft 20 and connected to a push rod 23 mounted on the platen 5 and having a thrust spring 24 operative to sweep the lever 22 across the 40 dead center of the lever action; that is, to extreme open or extreme closed positions. For the purpose of timing and initiating action of the grippers the lever 22 is provided with a striker or tappet 25 having opposite 45 effective positions, Figs. 6 and 7, at which to impinge on a tripping dog or pin 26 fixed in the end of an arm 27 which is fixed on a frame stud 28 and has a lever 29 connected by a link 30 to a cam lever 31 having a roller 50 32 engaging a timing cam 33.

When the grippers 21 are closed the dog 26 is tripped to inner position, Fig. 7, by the cam 33 in such time that the tappet 25 will move against the dog which will initiate 55 a rotation of the lever 22 and as this passes the axis of the push rod 23 the spring 24 completes the opening throw and moves the tappet just clear of the stationary dog 26; the platen moving in the direction of the arrow thereon. After the open gripper passes, the dog 26 is shifted to outer position, Fig. 6, so as to be engaged by the inverted tappet 25 which is tripped back to closing position, Fig. 7.

60 The grippers 21 are opened but once during

two revolutions of the impression platen; being controlled by the main cam shaft 4, for a reason later set forth.

Coordinate to the platen grippers 21 is a set of registering gages 35, Fig. 10, which have fingers straddling respective guide tongues 36 appropriately mounted on the lip of a feed-board.

As before stated there is capacity for a row of forms F along the form cylinder 2 and by this press each form may print at one impression a complete job on each advanced sheet or the several forms may be inked with different colors and the sheets to be printed may be progressively fed from the initial impression form to the final color imprint; being subjected to each form only once for its color imprint.

Therefore a system of stock registering gages is arranged on the feed board 37 in separate stations, one for each type form, so that sheets are registered with each form and, in time, advanced to the gang of platen grippers 21. Each registering station includes a fixed, adjustable guide gage strip 40 and an opposed, lateral shifting gage 41, of which a row is adjustably secured on a gage-shaft 42 journaled under the feed board 37 and having an attached spring 42^a tending to pull a shaft collar 43 endwise against a cam 44, Fig. 13.

The cam 44 is fixed on a sleeve 45 and has an arm 46 connected by a link 47 to a swinging hanger 48 on the frame 15 and which is connected to a driver link 49 operated by a cam lever 50 whose roller 51 rests on a suitable cam 52 on cam shaft 4. This mechanism is operative to oscillate the cam-arm 46 and cause the cam 44 to positively push the shaft 42 endwise and shift all of the lateral gages 41 and the interposed sheets over against the fixed gages 40.

One gage 35 is arranged to each feed station and opposed to this is a respective back gage 54 which is adjustable on a ledge 55 which is secured at its forward end to a strap 56. Each station has a strap 56 and the gang is fixed at 56^a to one of a bed of parallel rollers 57 having spindles 57^a journaled in a common plane in a rack-frame 58 which is secured on the reciprocating shaft 42. The ends of the spindles 57^a are slidably mounted in spaced bearing frame cheeks 59.

For the purpose of concurrently advancing the back gages 54 a belt 60 encompasses the bed of rollers 57 and a drive pulley 61, Fig. 14, which is secured on the sleeve 45, and to insure action of the intermediate rollers 57 transmission belts 62 connect them to the outer rollers in the rack-frame 58.

From the above it will be seen that the cam 44 has the dual function of side shifting the roller frame 58 and its shaft 42 with its gages 41, and at the same time forwardly turning 100

the rollers 57 to advance the row of back gages 54.

The effect of this coordinate gage and roller action is to diagonally shift all sheets at the stations #1, 2, 3 and 4 until they stop against the fixed side gages 40 and the register gages 35.

At moment of sheet register the grippers 21 are automatically closed on the leading edges 10 of the sheets S (Fig. 5).

In order to clear the register gages 35 from the sheet as it is taken by the grippers 21, means are provided to lift the gang of gages 35 from the tongues 36. To that end the gages 35 are each shown as adjustably clamped by screws 65 and 66 Fig. 10, to a shiftable block 67, a gang of which is set on a rock-shaft 68 journaled at its ends in arms 69 pivoted at bearings 70.

20 The rock-shaft 68 has side levers 71 tied at the top by a tie-rod 72 and having, on one lever 71, a cam roller 73 thrust against a cam wall 74 by a push rod 75 impelled by spring 76.

25 One of the arms 69, Fig. 2, has an adjustable stop-screw 77 engageable with the top of the feed-board to regulate the engagement of the gages 35 with the underhanging guide tongues 36. This arm is also provided with 30 an adjustable lift-screw 78 which overhangs the top of a lift-rod 79 whose lower end is connected to a cam lever 80 having a roller 81 running on a cam 82 whose timed action is to push up the arms 69 and carry the gages up 35 free of the registered stock but also to move them back of and higher than the tops of a gang of sheet return rollers 83 set on a spindle 84, journaled in the bearings 70, and having a drive pinion 85 meshing with the platen 40 gear 7.

The cam wall 74 is, therefore, so designed as to pull the gages 35 back and above the rollers 83 by tilting the levers 71 as the arms 69 swing up.

45 Following this action the platen carries the gripped row of sheets simultaneously to respective forms F and then continues to turn until the grippers make more than a full turn and register with a row of stripper fingers 86, 50 at which instant the grippers 21 are opened by positioned stripper 26 and the sheet is free to peel off and slip on to a row of boosting fingers 86a. The boosters are secured on a rock-shaft 89 which is oscillated by a link and 55 its cam 90 secured on the shaft 6. As the sheets are passed under the guide tongues 36 a cam actuated link 37a lifts the feed-board 37 to elevate the tongues from the path of the wet, printed sheets and then lowers them after 60 the sheet is clear of the platen.

The boosters 86a support the leading edge of the paper sheets and aid in carrying them over onto a mechanism which has the function of switching the sheets laterally from one receiving stage, from an impression form,

cross-wise to a return stage opposite the next form and its respective feed gage station, that is station #2, for advance to and registration with the #2 form.

The switching mechanism is positioned to receive sheets as they are advanced off the platen 5 under a lower set of rollers 91 on a shaft 92 having end wheels 93 tracking on the rims 11 of the platen. The switching mechanism also acts to elevate the switched sheets to a plane at the top of the rollers 91 to be passed thereby under a set of floating pressure rollers 94 on a spindle 95 playing in a yoke 96. The rollers 91-94 form a carry-over device for the returning sheets.

The switch and elevator means includes a horizontal frame 100 whose rear end is pivoted on a rod 101 on rear horns of the press frame 15. The elevator frame 100 is supported on and moved upward by an elevating link 102 whose lower end is attached to an arm 103 having a roller 104 running on a cam 105. In close sequence to the delivery of a batch of printed sheets from the rotary platen 5 the frame 100 is elevated and carries a set of switch rollers 106, on which the sheets are deposited from the platen, up to a position where the sheets will be in the top plane of the feed-back roller 91 to be passed thereby back on to the next registering station in the feed-board.

The switch rollers 106 are parallel and longitudinal of the press and are automatically turned concurrently in one direction by suitable means as a belt or chain 107 engaging ends of the rollers and being driven by a pinion 108 on a counter shaft 109 which is driven by a suitable means, as a sprocket chain transmission 110 leading from an intermittent drive shaft 111.

The shaft 111 is pivoted at one end in a swivel 112 and has a friction pinion 113 to periodically engage a friction disc 114 which is fixed on the drive shaft 9.

The pinion 113 is splined on its shaft 111 and is shiftable by a yoke 115 to change its speed by varying its radial position on the disc 114. The yoke 115 is splined on a rock-shaft 116 which has an arm 117 with a roller 118 engaging a cam 119, on cam shaft 4. One end of the intermediate shaft 111 is mounted in a sliding block 120, in a frame bracket, and a spring 121, Fig. 3, serves to press the pinion 113 out of driving contact and to press the cam roller to its cam 119.

The cam 119 is timed to close the friction drive device 113-114 as soon as a batch of sheets is deposited on the rollers 106 so that these will switch all sheets sidewise to the next stage for return to the registering gage stations # 2, 3 and 4.

The switch stages are determined by means of vertical stops or interceptors 125 which are carried by shanks 126 extending back to and adjustably secured on a rock-shaft 127

actuated at intervals by a push link 128 connected to a lever 129 having a roller 130 engaging the cam 131, on a cam shaft 4. When the switch rollers 106 move the sheets side-
wise to given distance under the elevated interceptors 125, these are lowered to stop the sheets and at this time the switch rollers stop action.

The rear ends of the switched sheets are now engaged by a comb or rake bar 133, sliding on the frame 100, and connected by side bars 134 to a cross-bar 135 having side-arms 136 fixed on a rock-shaft 137 which has an arm 138 connected to a push link 139 actuated by a cam device 140. The comb 133 pushes the sheets while the gages 35 are elevated far enough to enter them between the return rollers 91—94 and by them over the rollers 83 which bolster the returning sheets over to the lowered feed board.

When a multicolor job is being run a sheet is fed back and forth from station #1 to station #4 (or other number of times according to number of color imprints) and from the last imprint form it is run off the roller frame 100 by a delivery roller 108^a at the far side of the press.

In running multicolor work it is desirable to insure a clean product of clear colors and eliminate intermixture of the different colors of ink. For this purpose ink is taken from the well 145 by a duck roller 145^a and delivered to a distributing roller which is divided into a number of longitudinally spaced sections 146 which preclude end creep of ink as it is passed to composition form rollers 147—148 engaging the forms F.

Roller 147 is engaged by a spreading roller having spaced section 149.

40 The rollers 146—149 are vibrated endwise by means of a vertical rock-shaft 150 having arms 151—152 with pins 153 engaging collars 154 on the shafts 155—156. The shaft 150 has an arm 157 connected by a link 158 to a crank 159 on the shaft 6.

The feed board 37 can be swung up and out of the way when making up the press.

What is claimed is:

1. In a printing press, a multiform cylinder, an impression platen and means for repeatedly feeding, returning and refeeding a single sheet to the cylinder for progressive imprint by the forms, and including mechanism transferring the sheets over the platen from side to side.

2. In a printing press, a number of gage stations, a corresponding number of printing forms, an impression means, means at one side of the latter to feed a sheet to the said means and the forms progressively, and means at the other side to return the sheets from the forms to the gage stations in sequence.

3. In a printing press, a movable multi-form carrier, an impression means coordi-

nate therewith, a set of gage stations at one side of the said means corresponding to the forms, a printed sheet receiver at the opposite side thereof, and means for feeding a sheet to the carrier for printing and delivery to the receiver, and switch-over and return means for returning sheets to the respective gage means.

4. In a printing press, a multiform carrier and an impression device, means at one side thereof to simultaneously feed a number of sheets thereto, and means at the opposite side thereof for receiving the printed sheets and simultaneously returning them to the feed means for refeeding them to the carrier, and means for discharging the finally printed sheets from the receiver.

5. In a printing press, an impression platen and a multiform cylinder, means for gag-
ing and feeding a row of sheets to the forms on the cylinder, means to receive the printed row of sheets and return them to the feed means for re-feed to the cylinder and including carry-over rollers and means to elevate sheets thereto above the platen, and means for discharging each finally printed sheet from the receiving means.

6. In a printing press, operating means including a plurality of printing forms arranged in a row, gage means to register a row of sheets with the forms, and means having control of a sheet and continuously operative to pass the sheet in one action from the initial gage to the initial form and then progressively to sequential gages and respective forms and including oppositely arranged feed means and receiving means and a carry-over device therebetween.

7. In a printing press, means carrying multiple forms and an impression device cooperative therewith, gage stations to register sheets with respective forms, means at one side of said device to feed a row of sheets to the forms, and a receiver at the opposite side of the device having means to switch the printed sheets sidewise and return them above the said device to respective sequen-
tial gage stations to pass to the next form in progression.

8. In a printing press, a set of guide tongues, a gang of return rollers superjacent thereto, a set of end gages engaging the tongues, means to raise the gages to a position above said rollers for return of sheets, and means to guide the gages clear of the rollers in raising and lowering actions.

9. In a printing press, a set of guide tongues, a gang of return rollers superjacent thereto, a set of end gages engaging the tongues, means to raise the gages to a position above said rollers for return of sheets, and means to guide the gages clear of the rollers in raising and lowering actions, and adjustable means to regulate the lower position of the gages.

10. In a printing press, a set of guide tongues, a gang of return rollers superjacent thereto, a set of end gages engaging the tongues, means to raise the gages to a position above said rollers for return of sheets, and means to guide the gages clear of the rollers in raising and lowering actions, said gages being mounted on a rock shaft, and movable side arms in which said shaft is operatively mounted.

11. In a printing press, a set of guide tongues, a gang of return rollers superjacent thereto, a set of end gages engaging the tongues, means to raise the gages to a position above said rollers for return of sheets, and means to guide the gages clear of the rollers in raising and lowering actions, said gages being mounted on a rock shaft having end levers one of which has a cam roller, and said guide means including a cam controlling the levers.

12. In a printing press, feed means and a movable impression member and means on the side opposite the feed means for receiving sheets from the member and including a bed of rollers onto which sheets float directly from the member, means to intermittently turn them uniformly, and an intercepting means to stop switching action of sheets supported and shifted by the rollers.

13. In a printing press, an impression member, a sheet feed means at one side thereof, and means for taking printed sheets from said member and means for re-passing them across and clear of the member to the feed means.

14. In a printing press, an impression member, a sheet feed means at one side thereof, means for taking printed sheets from said member and means for re-passing them across and clear of the member to the feed means, and feed gage over which the sheets are cleared by the repass means in repass to the feed means.

15. In a printing press, feed means and an impression member, and means at the side opposite from the feed means for receiving sheets from said member, and including a bed of rollers, means to intermittently turn the rollers uniformly to switch the sheets, means to intercept the switched sheets, and means for shifting the stopped sheets endwise of the rollers toward the feed means.

16. In a printing press, feed means and an impression member, means at the side opposite from the feed means for receiving sheets from said member, and including a bed of rollers, means to intermittently turn the rollers uniformly to switch the sheets, means to intercept the switched sheets, means for shifting the stopped sheets endwise of the rollers toward the feed means, and feed-back means taking the sheets from the rollers and passing them to the feed means for re-feeding to the impression member.

17. In a printing press, feed means and an impression member, means for receiving sheets directly from said member and including a bed of rollers and means to intermittently turn them, means to intercept switched sheets on the rollers and including a series of vertical members movable to and from the plane of the shifting sheets.

18. In a printing press, feed means and an impression member, a bed of rollers receiving sheets directly from said member, means to intermittently turn the rollers, means to intercept sheets switched by the rollers, and shifting combs engageable with edges of switched sheets to move them toward the feed means.

19. In a printing press, feed means and an impression member, a bed of rollers receiving sheets directly from said member, means to intermittently turn the rollers, means to intercept sheets switched by the rollers, shifting combs engageable with edges of switched sheets to move them toward the feed means, and feed-back means for taking the sheets from the rollers and passing them to the feed means for refeeding to the impression member and including upper and lower gangs of rollers between and by which the sheets are drawn.

FRED. H. VAN LOOZEN.
